UNITED STATES PATENT OFFICE

2,451,940

DOUGHNUT GLAZING MACHINE

Michel J. Gendusa, New Orleans, La.

Application October 17, 1946, Serial No. 703,847

1 Claim.

1

This invention relates to the art of baking and has special reference to the coating of articles such as doughnuts and the like.

More particularly the invention relates to a machine for coating such articles with liquid sugar, the machine being preferably termed a glazing machine since articles treated in such a manner are known in the trade as glazed articles.

One important object of the invention is to provide an improved, simple and efficient machine for glazing baker's products.

A second important object of the invention is to provide a machine for the purpose whereby both the upper and the lower sides of an article passing through the machine will be effectively glazed.

A third important object of the invention is to provide a machine for the purpose whereby the glazing of both sides of an article passing through the machine will be effected simultaneously.

A fourth important object of the invention is to provide a machine of this class wherein liquid sugar is kept in circulation during operation of the machine.

A fifth important object of the invention is to provide a novel machine of this class wherein the circulating system for the liquid sugar and the other parts contacted by liquid sugar may be easily and effectively cleaned so as to prevent clogging by crystallization of the liquid sugar when the machine is not in operation.

With the above and other objects in view, as will presently be apparent, the invention consists in general of certain novel arrangements of details and combinations of parts hereinafter fully described, illustrated in the accompanying drawings and particularly claimed.

In the accompanying drawings like characters of reference indicate like parts in the several views, and:

Figure 1 is a side elevation of a machine constructed in accordance with this invention.

Figure 2 is a fragmentary section on the line 2-2 of Figure 1.

Figure 3 is a fragmentary section on the line 3-3 of Figure 1.

Figure 4 is fragmentary section on the line 4-4 of Figure 2.

Figure 5 is bottom view of a portion of a spray pipe suitable for use in this invention.

Figure 6 is a section on the line 6-6 of Figure 5.

Figure 7 is a fragmentary elevation of portion of the invention, the view being taken from the side opposite Figure 1 and disclosing parts hidden in that figure.

Figure 8 is a fragmentary section on the line 8-8 of Figure 7.

In the embodiment of the invention as herein disclosed there is provided a pair of side frames of suitable structural material. Each of these side frames consists of a bottom member or sill 10 adapted to rest on a floor or other support. At the ends of each sill are uprights 11 which have their upper ends connected by longitudinal members 12. An intermediate upright member 13 connects each sill 10 with the corresponding member 12 of the respective frame side. The two side frames are suitably connected at the supply or input end of the device by a cross member 14 and at the output end by a similar cross member 15.

Supported between the side frames is a tank open at the top and having sides 16. At the output end of the machine the tank is shallower than at the input end and has a bottom which inclines downwardly from the output end toward the input end as at 17. From the input end of this bottom a vertical wall 18 extends downwardly to the bottom of the input end of the tank. This end of the tank thus forms a collecting pit or sump for holding a supply of the liquid sugar coating material.

Extending downwardly the bottom 19 of the sump is a pipe 20 which connects with a horizontal pipe 21 leading to the intake side of a pump 22. Extending from the output side of this pump is a pipe having a horizontal portion 23 and a vertical portion 24. The vertical portion 24 is connected at its upper end to a spray pipe 25 extending horizontally across the machine from side to side thereof and supported in brackets 26. The pump 22 is driven by a motor 27 and this motor also drives a reduction gear 28 of any well known type. This reduction gear 28 includes a sprocket 29. At the output end of the machine there is provided a shaft 30 which extends through the side walls of the tank and is journaled in bearings 31 carried by brackets 32 fixed to the outer faces of the tank side walls.

On one end of the shaft 30 there is fixed a sprocket 33 which is connected by a sprocket chain 34 with the sprocket 29. On the shaft 30 within the tank there is provided a pair of sprockets 35 each being positioned close to a respective side of said tank. The sprockets 35 are fixed by set-screws 36 or other suitable means to the shaft 30.

At the input end of the machine the tank sides have oppositely disposed slots 37 extending horizontally and having their upper and lower edges

55

reinforced by members 38 forming guides for crossheads as shown at 39. Each of the crossheads is provided with an adjusting screw 40 which is journaled against longitudinal movement in a boss or bearing 41. Each of the adjusting screws is provided with a head 42 formed to receive a suitable tool for rotating the screw. A shaft 43 is supported in these cross heads and on this shaft there is mounted a pair of sprockets 44 which are in edgewise alignment with the sprockets 35. A belt 45 connects the pair of sprockets 35 with the pair of sprockets 44, the belt having adjacent its edges the usual holes for receiving the sprocket teeth. It will now be plain that the crossheads and screws constitute belt tightener means. The belt 45 is nearly as wide as the tank and the upper run of this belt passes beneath the jet pipe 25 so that articles on the belt will receive the discharge from the jet holes 46. The belt 46 is made of any suitable porous material such as woven fabric. Beneath that portion of the belt below the jet pipe 25 the upper run passes over a plate 47 which is supported on angle brackets 48 secured to the inner faces of the tank sides. The purpose of the plate 47 is to prevent passage of the glazing liquid for a certain distance along the upper run of the belt. At the input end of the belt there is a feeder tray whereon the doughnuts or other articles to be glazed are placed for feeding onto the belt 45. This tray is shown at 49. At the output end of the machine there is a rack 50 on which suitable trays or pans may be placed to receive the glazed articles from the belt.

In order to be able to clean out the pump and the pipes connected thereto when the machine is shut down a shut off valve is provided in each pipe line close to the tank and close to the jet pipe, the latter being connected through a union so that the jet pipe may be disconnected for cleaning. In each pipe line there is connected a valve 52 for connection and control of suitable wash out and discharge hose or pipes. Also cleanout doors 53 are provided in the side walls 16 for access to the interior of the tank and the lower run of the belt for cleaning when desired.

In the operation of the invention a quantity of liquid sugar or other coating material is placed in the sump of the tank, the valves 51 are opened and the motor 27 is started. The liquid sugar

will be pumped from the sump and up to the jet pipe 25 to flow through the jet openings 46 onto the upper run of the belt 45 which is, at the time, moving slowly from left to right of Figure 1.

6 The doughnuts are fed from the tray 49 onto the belt and in passing beneath the jet pipe are sprayed with the glazing liquid. Since the pores of the belt are sealed beneath the jet pipe there will be an accumulation of glazing liquid above 10 the plate 47 and the under sides of the articles on the belt will be wet with the glazing liquid. After the upper run of the belt carries the doughnuts beyond the plate 47 the excess of the glazing material will pass down through the pores of the belt into the tank and will there flow down 15 the bottom 11 to the sump for recirculation. The doughnuts will be carried along and delivered at the output end onto trays supported on the rack 50.

20 What is claimed, is:

In a glazing machine for bakery products, an open top tank for containing glazing liquid, an endless woven fabric belt traversing the top of said tank, means for drawing liquid from said tank and delivering it onto successive lengths of said belt, said means including a jet pipe extending transversely above said belt having a multiplicity of jet holes on its under side and a pump having pipe connections with said tank and with said jet pipe, said belt having upper and lower runs, and a plate beneath the upper run of said belt and located beneath said jet pipe, the upper run of said belt moving over said plate resting on and in direct contact therewith 30 whereby the porosities of said belt are closed in that portion of the belt in contact with said plate.

MICHEL J. GENDUSA.
